UNITED STATES PATENT OFFICE.

JOHN W. LAUREN, OF STERLING, ILLINOIS.

WIRE POINTER.

Application filed July 10, 1922. Serial No. 573,851.

To all whom it may concern:

Be it known that I, JOHN W. LAUREN, a citizen of the Republic of Finland, and a resident of the city of Sterling, in the county of Whiteside and State of Illinois, have invented certain new and useful Improvements in a Wire Pointer; and I do hereby declare that the following is a full, clear, and exact description of the same, reference 10 being had to the accompanying drawings, and to the numerals of reference marked thereon, which form a part of this specification.

This invention relates to a wire pointing machine in which the blunt end of a wire is adapted to be inserted and reduced in diameter.

In the manufacture of wire tubes and small rods which are drawn through a die, 20 and also in the manufacture of rods by rolling, it is necessary to reduce the end of the wire or rods by an operation known as "pointing", so that they may be inserted through the die for clamping engagement 25 with the mechanism that draws them through the die. In the past, hydraulic pointers and machines having grooved rollers in which the wires had to be turned over were used for such a purpose. These prior 30 devices were more or less cumbersome and slow in operation and did not always point the wire in a true axial direction, and a more or less tapering point would be provided which would not afford the best grip 35 or afford an even pull.

It is an object of this invention to provide a wire pointing machine in which the above noted objections are overcome, and in which the wire is pointed to any desired 40 length in a true axial direction without the necessity of turning it during the pointing operation, and in which the pointing operation is carried on very rapidly and with but little effort on the part of the operator.

45 With these and other objects in view which will become more apparent in the following description and disclosures in the drawing, this invention comprises the novel mechanism and combinations hereinafter 50 described and more particularly pointed out and defined in the appended claims.

In the accompanying drawings which il-

lustrate a preferred embodiment of this invention and in which similar reference numerals refer to similar features in the 55 different views:

Figure 1 is a vertical sectional view of the machine with the motor in elevation.

Figure 2 is a sectional view of the rotor 60 in detached form.

Figure 3 is an end elevation of the machine.

Figure 4 is a part elevational and part cross-sectional view of the machine illustrating the arrangement of the rollers. 65

As shown on the drawings:

In the exemplification of this invention, there is illustrated a spider comprising two separable sections 1 and 2. The section 1 consists of a hollow bearing or journal 1^a 70 having a plurality of equally spaced and radially extending arms 3 at its inner end. The arms 3 terminate in longitudinally extending portions 3^a provided with bolt receiving apertures and reversely curved upon 75 their inner surfaces. The inner end of the section 1 is also provided with a plurality of equally spaced and radially extending arms 4 intermediate the arms 3; the arms 4 being provided with suitable journal 80 apertures.

The section 2 of the spider consists of a journal or bearing neck 2^a having a conical wire receiving aperture 5 extending axially therein which terminates in a cylindrical 85 hollow bore 6. The inner end of this section is fashioned similar to the section 1 with radial arms 3 having the horizontal apertured portions 3^a with intermediate arms 4. 90

The arms 3 and 4 of the two sections are similarly arranged and spaced, so that they may be brought into opposed relation and the two sections secured together by bolts 7 95 extending through the apertured arm portions 3^a. In the present instance, each section is provided with four radial arms 3 and four intermediate equally spaced radial arms 4.

Journals or shafts 8 are rotatably journaled in the radial arms 4 and circumferentially spaced upon a circle having the axis of the spider as a center and spaced circular disks or elements 9 are integrally united 100

with the shafts 8 for rotation therewith. The corresponding disks 9 are mounted on or integral with diametrically opposite shafts 8 and are positioned in the same vertical plane as shown in Figure 1 so as to coact with respect to a wire passed therebetween, but the coacting disks on one pair of diametrically opposite shafts 8 are positioned intermediate the coacting disks of the other pair of diametrically opposite shafts. The peripheries of said disks 9 may be smooth or may have a shallow continuous thread cut in their surfaces.

The outer peripheries of the disks 9 have a gentle outward slope or bevel in the same direction with respect to the axes of said disks. This outward slope extends from the left to the right as viewed in Figure 1 and the disks from left to right are of gradually increasing diameter whereby a gradually tapered way or opening is provided between the peripheries of the disks or elements 9, the way being concentric with the passages through the journal bearings of the rotor.

The above-described spider with the rotatable disks supported thereby constitutes a rotor which is rotatably mounted in a cylindrical housing 10 having a supporting base 11 (Fig. 4). The front end of the housing 10 is provided with a bearing aperture for receiving the journal 2^a of the rotor, while the rear end of the housing 10 is closed by a plate 11 having an inner rabbeted margin which fits the open end of the housing 10 to provide a fluid-tight fit. The plate 11 is provided with a suitable journal bearing to receive the journal 1^a of the rotor. The inner front wall of the housing 10 adjacent the bearing aperture is provided with a circular head 12 and the plate 11 is provided with a similar circular head 12. These heads act as end thrust bearings for the shafts 8, as can be readily seen by an inspection of Figure 1. The housing 10 extends some distance below the disks or elements 9 to provide a lubricant chamber for supplying lubricant to the disks.

The journal 1^a of the rotor projects beyond the journal bearing of the plate 11 for the purpose of receiving a gear or sprocket 13 which may be suitably keyed thereon. In the present instance, in which sprocket gearing is used, a sprocket chain 14 is trained over the sprocket wheel 13 and also over a sprocket wheel 15 secured upon a motor shaft, the motor 16 of which is supported upon the housing 10.

In the operation of the machine, the motor 16 is started to drive the rotor at a very high rate of speed, the wire to be pointed is then inserted through the conical bore 5 of the rotor and pushed between the elements 9 which are bodily rotated by the rotor and which have relative rotation with

respect to the rotor. The action of the elements 9 on the wire will quickly reduce the diameter thereof by causing an elongation thereof. The action of the element 9 on the wire is a kind of squeezing action which uniformly reduces the diameter of the wire by elongating the same, so that a pointed wire will have the shape as illustrated by the specimen 17 in Figure 1, which has just been acted upon by the revolving elements 9. The tendency of the wire to become locked between the disks 9 so as to bodily rotate with the rotor and twist is overcome by the relative rotation of the disks 9 with respect to the rotor. The action of the disks 9 tends to rotate the wire in a direction reverse to the rotation of the rotor. The end of a wire may be pointed to any desired length as is apparent, and when it has been sufficiently pointed, it may be readily withdrawn from the machine and a new one inserted.

The machine of this invention may be conveniently used for reducing the diameter of rods or tubes which are produced by the hot rolling process, the machine being positioned to receive the rods directly from the rolls, and after the diameters of the rods have been reduced thereby, they may be wound directly upon a suitable reel.

From the foregoing, it will be apparent that this invention broadly comprises a rotor having relatively rotatable elements supported therein between which the end of a wire, rod, or tube may be speedily reduced without the necessity of manually turning the wire and in which the end or the entire length of the wire, rod, or tube is pointed or reduced in a true axial direction.

I am aware that numerous details of construction may be varied through a wide range without departing from the principles of this invention, and I therefore do not purpose limiting the patent granted hereon otherwise than necessitated by the prior art.

I claim as my invention:

1. In a wire pointing machine, a housing having end journal bearings and a lubricant chamber, a rotor having hollow end journals mounted in said bearings, said rotor having radially extending arms, shafts journaled in said arms, disk rollers secured upon said shafts and adapted for passing through the lubricant in said chamber and means for rotating said rotor.

2. In a wire pointing machine, a housing having a lubricant chamber and end journal bearings, a rotor having hollow end journals mounted in said bearings, a plurality of circumferentially spaced shafts carried by said rotor, bevelled disk rollers of gradually increasing diameter to define a tapered way upon said shafts and adapted for passing through the lubricant in said chamber and means for rotating said rotor.

3. In a wire pointing machine, a stationary housing having a lubricant chamber, a rotor journaled in said housing and having an axial opening for the passage of a wire, a plurality of shafts carried by said rotor, each shaft supporting a series of bevelled rollers of gradually increasing diameter to define a tapered way, said rollers being adapted for passing through the lubricant in said chamber, and means for rotating said 10 rotor.
- 5 In testimony whereof I have hereunto subscribed my name.

JOHN W. LAUREN.
